(57) **CLAIM**

The ornamental design for a firearm holster adapter, as shown and described.

DESCRIPTION

FIG. 1 is a perspective view of a first embodiment of a firearm holster adapter showing our new design;

FIG. 2 is another perspective view of the firearm holster adapter shown in FIG. 1;

FIG. 3 is a front elevational view of the firearm holster adapter shown in FIG. 1;

FIG. 4 is a right side elevational view of the firearm holster adapter shown in FIG. 1;

FIG. 5 is a left side elevational view of the firearm holster adapter shown in FIG. 1;

FIG. 6 is a rear elevational view of the firearm holster adapter shown in FIG. 1;

FIG. 7 is a top plan view of the firearm holster adapter shown in FIG. 1;

FIG. 8 is a bottom plan view of the firearm holster adapter shown in FIG. 1;

FIG. 9 is a perspective view of a second embodiment of a firearm holster adapter showing our new design;

FIG. 10 is another perspective view of the firearm holster adapter shown in FIG. 9;

FIG. 11 is a front elevational view of the firearm holster adapter shown in FIG. 9;

FIG. 12 is a right side elevational view of the firearm holster adapter shown in FIG. 9;

FIG. 13 is a left side elevational view of the firearm holster adapter shown in FIG. 9;

FIG. 14 is a rear elevational view of the firearm holster adapter shown in FIG. 9;

FIG. 15 is a top plan view of the firearm holster adapter shown in FIG. 9; and,

FIG. 16 is a bottom plan view of the firearm holster adapter shown in FIG. 9.

(Continued)

The broken lines represent portions of the firearm holster adapter that form no part of the claimed design.
